2 Sheets-Sheet 2

UNITED STATES PATENT OFFICE.

GEORGE N. TAYLOR, OF EAST PROVIDENCE, RHODE ISLAND, ASSIGNOR TO UNIVERSAL WINDING COMPANY, OF BOSTON, MASSACHUSETTS, A CORPORATION OF MASSACHUSETTS.

WINDING MACHINE.

Application filed April 28, 1923. Serial No. 635,261.

This invention relates to improvements in winding machines and particularly to an adjustable traverse-mechanism for controlling the traverse of the material on the rotating winding-spindle or other mandrel or holder.

One object of the invention is to provide a more simple and efficient traverse mechanism for reciprocating the guide or other element which causes the material to be traversed back and forth to deposit it in helical turns forming the superimposed layers of winding.

Another object of the invention is to provide a traverse-mechanism adapted for more precise and accurate adjustment within wide limits to regulate the extent of traverse of the material in accordance with varying requirements.

Another object of the invention is to provide a traverse-mechanism which is more economical to manufacture and less subject to wear in use.

Another object of the invention is to provide a traverse-mechanism which is susceptible of adjustment during the operation of the machine.

Further objects of the improvement are set forth in the following specification which describes a preferred embodiment of the invention as illustrated in the accompanying drawings. In the drawings:

Fig. 1 is a plan view of the improved traverse-mechanism, showing it in connection with the essential elements of the winding head or unit which it operates;

Fig. 2, a transverse sectional view of the same taken on the line 2—2 of Fig. 1;

Fig. 3, a longitudinal sectional view of the winding head taken on the line 3—3 of Fig. 1; and

Fig. 4, a detail view showing the arrangement of the traverse-guide which is operated from the traverse-mechanism.

The present improved traverse-mechanism is adapted for use with various types of winding machines and, by way of example, is herein illustrated in connection with a coil-winder for winding wire or other conductor into electrical coils. Referring first to Fig. 1 of the drawings, the present type of machine comprises one or more winding heads or units 2 (only one being shown) which may be arranged in series to be oper-

ated from a single driving-means and traverse-mechanism. As shown more particularly in Fig. 3, the winding-mechanism comprises a drive-shaft 3 journaled in bearings 4 in the frame or casing 5 and carrying a helical gear 6 which meshes with a similar gear 7 on the winding-shaft or spindle 10.

The winding-spindle 10 is journaled in bearings 9 in the casing 5 and the gear 7 is free to turn thereon, being adapted for rotative connection therewith by means of a suitable clutch-device 11. The clutch 11 is not herein shown in detail as it may be of any suitable construction as usually employed in machines of the present type. Suffice it to state that the clutch-member 12 is keyed to the spindle 10 and normally held in engagement with the gear 7 by means of a coiled spring 14 bearing against a collar 15. A tapered flange 16 on the clutch-member 12 is adapted to be engaged by a shoe 17 on a suitable lever 18, see Fig. 1, whereby the clutch may be released, either automatically or manually, to disconnect the winding-spindle 10 from the drive in the usual manner as well known to those versed in the art.

The winding-spindle 10 projects outwardly beyond the end of one of its bearings 9 and carries a chuck 19 for holding a core or spool 20 on which the wire *w* or other conductor is wound to produce a coil of any desired form and dimension.

Arranged in opposite, parallel relation with the winding-spindle 10 is a traverse-bar or rod 22 adapted to slide in suitable bearings in the casing 5 and connected to the traverse-mechanism to be reciprocated therefrom to operate the traverse-guide 25. The guide 25 consists of an arm 26 having a hub 27 secured to the traverse-rod 22 by any suitable means such as the binding-screw 28. At the outer end of the arm 26 is a grooved guide-wheel 30 around which the wire *w* leads to the winding-mandrel or spool 20 in the manner as shown in Fig. 4. It will be understood that the traverse-rod 22 may extend through a series of the frames or casings 5 to carry the guides for a plurality of winding units; and likewise, the main drive-shaft 3 may be extended for driving connection with all of the winding-spindles of the several heads.

As before indicated, the traverse-mecha-

nism for the single or plural winding-heads constitutes a separate unit which is combined with the mechanism for driving the machine and contained in a casing or box 31 shown in Figs. 1 and 2. As here illustrated a power-shaft 32 is journaled in bearings 33 in the casing 31 and projects therefrom at one end to adapt it to be coupled to the drive-shaft 3 for the winding units. Any suitable coupling-means such as that shown at 29 may be employed for rotatively connecting the shafts 32 and 3, or if preferred, a single continuous shaft without couplings may be used. At its opposite end the shaft 32 carries a belt-pulley 34 or any suitable means for connecting it with a motor or other source of power. Midway between the bearings 33-33, the shaft 32 carries a screw or worm 35, preferably formed integral therewith, and adapted to mesh with a worm-gear 36. The gear 36 is journaled on the reduced end of a vertical stud-shaft 37 held fixedly in a bearing 38 formed as a part of the casing 31.

A heart-shaped cam 40 is mounted to turn on the upper reduced end of the stud-shaft 37 and is secured rotatively with the gear 36 by means of a screw 41 which binds it against the face of the gear. The cam 40 is adapted to reciprocate a slide 45 which carries opposite rollers 46 arranged to travel on the peripheral surface of the cam.

As shown in Figs. 1 and 2, the slide 45 may consist of a relatively flat rectangular plate resting on top of the cam 40 and slidable in a guideway 47 formed as a part of a circular disk or turntable 48. The disk 48 is seated in a circular, flanged recess 49 formed in a horizontal web or partition 50 extending across the casing 31 and supported from its sides. The guideway 47 for the slide 45 may be constructed as a slot or trackway extending diametrical- 40 ly of the disk 48 and provided with opposite, parallel bearing surfaces 44 between which the slide is received. The disk 48 is adapted for rotative movement in its recess 49 in the web 50 and may be secured in position by any suitable means whereby to maintain the guideway 47 in its adjusted relation as shown in Fig. 1. As here illustrated, the disk or turntable 48 is held in its recess and clamped fixedly in position by means of suitable bolts 51 screwed down into the web 50 with their heads binding against washers 52 overlapping the edge of the disk.

The traverse-rod 22, previously referred to, extends across the top of the turn-table 48 with its axis intersecting the axis of the worm-gear 36, being slidably mounted in bearings 54 projecting inwardly from the sides of the casing 31. On the traverse-rod 22 is a crosshead 55 having a hub 56 secured to the rod by a set-screw 57 or any

other suitable means. The crosshead 55 overlies the slide 45 and is provided with a slot or groove 58 on its under side adapted to be engaged by a roller 60 journaled on a stud 61 projecting upwardly from the slide. The slot 58 extends at right-angles to the axis of the traverse-rod 22 and it is therefore obvious that as the slide 45 is reciprocated in its guideway 47 under the turning action of the cam 40 the roller 60 will play back and forth in the slot to impart a reciprocating motion to the crosshead 55. The method of operation of the complete machine is as follows:

When power is applied to the pulley 34 on the shaft 32 the latter drives the connected shaft 3 for one or more winding units, and rotation is transmitted therefrom to each winding-spindle 10 through the gears 6 and 7 and clutch 11. The core or spool 20 carried by the chuck 19 on the spindle 10 will thus be rotated to wind on the wire or other strand *w* as the latter leads through the groove in the guide wheel 30 which directs it to the coil as shown in Figs. 3 and 4.

Referring now to Figs. 1 and 2 the power-shaft 32 also drives the gear 36 from the worm 35 to rotate the heart-cam 40 with a relatively slow motion. The cam 40 is thus caused to reciprocate the slide 45 through the engagement of the cam with the rollers 46 the extent of this movement of the slide in its guideway being constant as defined by the eccentricity of the cam 100 with respect to the axis of the gear 36 with which it revolves. As before explained the slide 45 is connected by its roller 60 to reciprocate the crosshead 55 and the extent of throw of the crosshead is regulated 105 by the degree of inclination of the path of the slide to the slot 58 in the crosshead. The length of stroke of the crosshead 55 determines the extent of reciprocation of the traverse-rod 22 and hence governs the 110 length of traverse of the guide 25 which deposits the windings on the core or spool 20.

The machine is adapted to wind coils of varying lengths by adjusting the traverse 115 of the guide 25 in accordance with requirements and such adjustment is accomplished as follows: Before starting the winding the clamp-bolts 51 for the turntable 48 are loosened so that the latter may be adjusted 120 rotatively about the axis of the cam 40. The turntable may be adjusted while the machine is being turned over by hand, or running under power, and the guideway or track 47 may be inclined at varying 125 angles to give an accurate and minute degree of adjustment in regulating the throw of the guide 25 within the prescribed limits. It will be obvious that if the guideway 47 is set in parallel relation with the 130

transverse-rod 22, or in other words, in line with the path of movement of the cross-head 55, the latter will be given a stroke equal in length to the full stroke of the 5 slide 45. By turning the turntable 48 to set the guideway 47 at an angle to the path of movement of the crosshead 55 the operative effect of the reciprocating motion of the slide 45 is altered to shorten the stroke of 10 the crosshead 55 and that of the guide 25 reciprocated therefrom. That is to say, as the guideway 47 is inclined away from the axis of the rod 22 the extent of reciprocation of said rod will be gradually shortened 15 until, when the guideway has been turned through an arc of ninety degrees, the movement of the slide 45 will be at right-angles to the rod 22 and hence the roller 60 will slide back and forth in the groove 58 of the 20 crosshead 55 without imparting any motion to the traverse-rod.

It will thus be seen that the traverse or stroke of the guide 25 may be adjusted from a maximum equal to the full stroke of the 25 slide 45 down to a minimum of zero and with the utmost degree of exactness between these points. The traverse of the guide may therefore be regulated in accordance with the requirements of all sizes of coils required up to the maximum capacity of the 30 machine with a minute degree of adjustment heretofore unobtainable in machines of the present type.

It is also to be noted that my improved 35 device makes for greater facility and convenience in the adjustment of the traverse besides providing for such adjustment without stopping the machine. That is to say, if the stroke of the traverse-guide requires 40 further adjustment after the machine is started, such adjustment may be made without stopping the winding.

It is further called to attention that in the present improved device the adjustment 45 of the traverse is made without change or replacement of any of the elements of the mechanism so that the machine need not be taken apart or disassembled. Moreover, the improved device is extremely simple in construction, positive in action and proof 50 against derangement or getting out of order.

While I have herein illustrated and described one preferred embodiment of the 55 invention it is to be understood that various modifications may be made in the structure and arrangement of its parts which would fall within the scope of the appended claims. I claim.

1. In a mechanical-motion, the combination of a normally stationary adjustable turntable, a guide angularly adjustable with the turntable, a slide slidable on the guide, a cam rotatable on the axis of the turntable, means connecting the cam to recip-

rocate the slide, a crosshead reciprocable across the axis of the turntable, and means connecting the slide to reciprocate the cross-head.

2. In a mechanical-motion, the combination of a rotatable cam, a member reciprocable across the axis of the cam, a guide angularly adjustable about the axis of the cam, to adapt it to be set in different positions of inclination with respect to the path of movement of the reciprocable-member, a slide slidable on the guide, means connecting the cam to reciprocate the slide, and means connecting the slide to actuate the reciprocable-member with different lengths of stroke in accordance with the adjustment of the guide. 70 75

3. In a mechanical-motion, the combination of a rotatable cam, a member reciprocable across the axis of the cam, a guide extending across the axis of the cam and adjustable in angular relation with respect to the path of movement of the reciprocable-member, a slide on the guide reciprocable from the cam, and means connecting the slide to actuate the reciprocable-member with a length of stroke as determined by the angular adjustment of the guide. 80 85 90

4. In a mechanical-motion, the combination of a rotatable cam, a slide connected to be reciprocated from the cam, a guide for determining the direction of movement of the slide, means to adjust the guide angularly about the axis of the cam, a member reciprocable across the axis of the cam, and means connecting the slide to reciprocate said member with different lengths of stroke in accordance with the angular adjustment of the guide. 95 100

5. In a mechanical-motion, the combination of a cam, a slide slidable across the axis of the cam, a member rotatably adjustable about the axis of the cam and provided with a guide for the slide, means connecting the cam to reciprocate the slide on the guide, and a member connected to be reciprocated from the slide with different lengths of stroke as determined by the angular adjustment of the guide. 105 110

6. In a mechanical-motion, the combination of a casing, a cam rotatable within the casing, a turntable rotatably mounted on the casing concentric with the axis of the cam and provided with a guideway, a slide slidable on the guideway and connected to be reciprocated from the cam, a rod reciprocable across the axis of the cam, a crosshead on the rod, and means on the slide engaging the crosshead to impart reciprocation to the rod. 115 120 125

7. In a mechanical-motion, the combination of a relatively stationary rotatively adjustable turntable, a trackway on said turntable, a slide slidable on the trackway, a member reciprocable across the axis of the 130

turntable, a crosshead on said member, and means on the slide engaging the crosshead and slidable thereon to connect the slide to reciprocate said member with a length of 5 stroke variable in accordance with the angular adjustment of the trackway with respect to the direction of movement of the reciprocable member.

8. In a mechanical-motion, a guideway, a 10 slide reciprocable in the guideway, means to reciprocate the slide, a reciprocable crosshead formed with a lateral slot, means on the slide engaging the slot in the crosshead, and means for adjusting the guideway to

vary the direction of movement of the slide 15 with respect to the plane of movement of the crosshead.

9. In a mechanical-motion, the combination of a heart-shaped cam, means to rotate the cam, a slide, rollers on the slide engaging the periphery of the cam, a guideway on which the slide slides, means to adjust the guideway in angular relation about the axis of the cam, a crosshead reciprocable across the axis of the cam, and means connecting the slide to reciprocate the crosshead. 20 25

In testimony whereof I affix my signature.

GEORGE N. TAYLOR.
